UNITED STATES PATENT OFFICE.

BERTRAM S. ROTHWELL, OF CLEVELAND, OHIO.

OIL BURNER.

1,398,650.

Specification of Letters Patent. Patented Nov. 29, 1921.

Application filed October 1, 1919. Serial No. 327,729.

To all whom it may concern:

Be it known that I, BERTRAM S. ROTHWELL, a citizen of the United States, and a resident of Cleveland, county of Cuyahoga and State of Ohio, have invented a new and useful Improvement in Oil-Burners, of which the following is a specification, the principle of the invention being herein explained and the best mode in which I have 5 contemplated applying that principle, so as to distinguish it from other inventions.

The present invention relates to oil burners of the type used in heating furnaces, muffles and the like. More particularly the 15 invention relates to the construction of the burner and of the mixing mechanism. The present burner has been designed to operate on very low air pressure and it provides means for thoroughly mixing a large body 20 of air at low air pressure with the necessary oil vapor prior to its emission from the burner nozzle. Other features are the arrangement of the parts so as to be easy of assembly and replacement. To the accomplishment of the foregoing and related ends, said invention, then, consists of the means 25 hereinafter fully described and particularly pointed out in the claims.

The annexed drawing and the following 30 description set forth in detail certain mechanism embodying the invention, such disclosed means constituting, however, but one of various mechanical forms in which the principle of the invention may be used.

35 In said annexed drawing:

Figure 1 is a central longitudinal section of my improved burner; Fig. 2 is a perspective view of the fuel valve; Fig. 3 is a broken perspective view partially in section 40 of the mixing device, and Fig. 4 is a broken perspective of the inner portion of the mixer shown in Fig. 3.

The burner proper consists of a T-joint 1 having a flange 2 on a leg of the T which is 45 adapted to be bolted or otherwise secured to an air supply pipe and also to support the burner. The ends of the T-joint are threaded and on the forward end is mounted a cap 4 having a suitable, centrally located 50 aperture 5. This cap is, of course, adjustable longitudinally of the burner and the aperture acts as the outlet opening or nozzle for the burner.

On the rear end 7 of the T-joint a second 55 cap 6 is threaded which has a hollow exten-

sion 8 provided with a threaded aperture 9 in the side thereof. This extension is threaded as at 10 for a portion of its length and is provided with a small cap 11 so that the device may be packed to be air tight. 60 The opening 9 in the side of the extension is adapted to be connected to the fuel line and this opening leads into the hollow portion of the extension and into a fuel conduit 12 which is threaded into the cap from 65 the interior thereof. A valve stem 13 is mounted through the extension and has a threaded portion 14 engaging with screw threads 15 formed on the interior of the extension. This valve stem extends through 70 the fuel conduit and has at its forward end a valve portion 16 comprising a cylindrical portion 17 having a spiral groove 18 and a cone shaped end 19, into which the spiral groove extends. At its rear end the valve 75 stem extends through the small cap 11 and is provided with a handle 20 by which it may be adjusted.

Mounted on the forward end of the fuel conduit is the cone shaped mixing device 80 which is of particular interest in the present connection. This mixer has a central portion 21 interiorly threaded as at 22 and adapted to be carried on the threaded forward end of the fuel conduit. This central 85 portion is provided with a small centrally located aperture 23 with flared sides at its inner end, opening to the fuel conduit, forming a valve seat 24 for the valve heretofore mentioned. Around this central portion are 90 mounted two concentrically arranged cone shaped sleeves, the inner sleeve 25 being attached to the central portion by means of spiral blades 26 which are curved in the opposite direction to the spiral groove in the 95 valve. This inner sleeve 25 extends forwardly of the outlet 23 in the central portion forming a mixing chamber 28. The second cone shaped sleeve 29 is spaced from the first and between the two are other spiral 100 blades 30 turned oppositely to the blades 26 between the first sleeve and the central portion. This sleeve 29 extends beyond the first sleeve 25 forming an additional mixing chamber 31. This outer sleeve is of less 105 diameter at its forward end than the aperture in the cap, thus leaving an angular opening 32 between the same, the sleeve being adapted to be approximately in line 110 with the inner surface of the cap.

The air is adapted to pass between the two sleeves and between the inner sleeve and the central portion as well as between the outer sleeve and the T-joint. The oil is supplied past the valve by which it is given a spiral motion so that it flows out of the aperture in the form of vapor or spray with a whirling motion from left to right. At this point it is mixed with a blast of air which flows between the central portion and the inner sleeve and which blast is given a whirling motion in the opposite direction to the oil vapor or from right to left. The air and the oil vapor is thus mixed in the first chamber 28 and then flows outwardly where it meets with the second air blast from between the two sleeves and which is whirling from left to right and is thus more thoroughly mixed in the second mixing chamber 31. The mixture then flows out from the second mixing chamber 31 to the aperture in the cap where it meets with the third air blast coming in around the outer sleeve 29 before it passes out of the opening in the cap which acts as the burner nozzle.

Heretofore oil burners have usually been operated by means of an air blast under considerable pressure, the air and the oil being sprayed out of the nozzle and into the furnace where they are burned. In the present device the air capacity is large and the air is supplied at a very low pressure, approximately 16 to 18 oz. being sufficient, while the oil is supplied under pressure of about 15 lbs. By means of the large air openings it has been found possible in a 2 inch burner to use approximately 25 cubic feet of air per minute per gallon of fuel per hour.

Marked advantages are obtained by using the air under low pressure and supplying it in a large volume so that it is thoroughly mixed with a fuel vapor before being delivered to the furnace. The actual mixing occupies three steps, the air being blown into the fuel vapor through three angular openings, the blades within the openings giving the air a whirling action, first in one direction and then in another so that complete mixing and vaporization is obtained before the mixture is burned.

The construction of the burner is such that the entire mixing device may be readily removed without disturbing the burner itself. By disconnecting the fuel line the entire mixer may be removed by unscrewing the rear cap 6 as the fuel conduit and mixer are carried by this cap. The valve and valve stem are also carried by the cap and may be removed by unscrewing the small cap on the extension. The parts may thus be readily cleaned and replaced or new parts inserted as required, quickly and readily no special tools being required. The cost of

manufacture, assembly and repair is thus reduced and a very simple and satisfactory burner produced.

The adjustment and control of the burner is readily accomplished, the oil being controlled by the valve and the character of the flame by means of the adjustable front cap. The operation and adjustment is simple and does not require a skilled operator, and it has been found that the burner does not smoke, smell or drop oil at any time during its operation. With this burner it has been found easily possible to maintain from 2500° to 3000° of heat upon the fuel consumption mentioned above.

Other modes of applying the principle of my invention may be employed instead of the one explained, change being made as regards the mechanism herein disclosed, provided the means stated by any following claims or the equivalent or such stated means be employed.

I therefore particularly point out and distinctly claim as my invention:

1. In an oil burner, the combination of T-joint casing, having an air inlet, a cap removably attached to said T-joint, a fuel conduit removably attached to said cap and extending forwardly of said T-joint, and a mixing member removably attached to said conduit and consisting of a series of cone shaped sleeves, spaced from each other and attached to each other by spiral blades, the blades between successive sleeves spiraling in opposite directions.

2. In an oil burner, the combination of T-joint burner casing having threaded ends, and an air inlet and aperture cap adjustably mounted on the forward end, a cap removably mounted on the rear end, a fuel conduit removably attached to said rear cap, extending forwardly of said casing, and a cone shaped mixing device removably attached to said conduit and comprising a central portion having a fuel outlet, a cone shaped sleeve spaced from said central portion and extending therebeyond, spiral blades between said central portion and said sleeve, a second sleeve spaced from said first sleeve and extending therebeyond to form an elongated mixing chamber, and spiral blades between said two sleeves, said last named blades being curved oppositely to said first named blades.

3. In an oil burner, the combination of T-joint burner casing having threaded ends, and an air inlet, an aperture cap adjustably mounted on the forward end, a cap removably mounted on the rear end, a fuel conduit removably attached to said rear cap and extending forwardly of said casing, and a cone shaped mixing device removably attached to said conduit and comprising a central portion having a fuel outlet, a cone shaped sleeve spaced from said central portion,

spiral blades between said central portion and said sleeve, a second sleeve spaced from said first sleeve and spiral blades between said two sleeves, said last named blades being 5 curved oppositely to said first named blades, said inner sleeve extending beyond said central portion and thus forming a mixing chamber, said second sleeve extending beyond said first sleeve and forming a second 10 mixing chamber.

4. A mixing device for oil burners consisting of a cylindrical casing having an outlet opening, and a mixer mounted adjacent such opening, said mixer comprising 15 a central portion having a fuel outlet adapted to spray such fuel in a spiral direction, a sleeve surrounding such central portion and spaced therefrom, said sleeve extending in front of said central portion to form a mixing 20 chamber, spiral blades between said sleeve and said central portion to give a whirling action to the air in the opposite direction to the whirling of such fuel, a second sleeve spaced from said first sleeve and 25 extending in front thereof to form a second mixing chamber, spiral blades between said two sleeves to give a whirling action to the air in the same direction as the whirling 30 action of the fuel, said second sleeve extending to approximately the outlet opening but

being smaller to leave an annular opening as an additional air inlet.

5. A mixing device for oil burners consisting of a cylindrical casing having an adjustable cap provided with an outlet opening, and a mixer mounted adjacent such opening, said mixer comprising a central portion having a fuel outlet adapted to spray the fuel in a spiral direction, a sleeve surrounding said central portion and spaced 35 therefrom, said sleeve extending in front of said central portion to form a mixing chamber, spiral blades between said sleeve and said central portion to give a whirling action to the air in the opposite direction to 40 the whirling of such fuel, a second sleeve spaced from said first sleeve and extending in front thereof to form a second mixing chamber, spiral blades between said two sleeves to give a whirling action to the air 45 in the same direction as the whirling action of the fuel, said second sleeve being of less diameter than such outlet opening to leave an annular opening for additional air, said cap being adjustable to vary such annular 50 opening.

Signed by me, this 26th day of September, 1919.

BERTRAM S. ROTHWELL.
